JEROME FASSLER, OF SPRINGFIELD, OHIO.

Letters Patent No. 65,192, dated May 28, 1867.

IMPROVEMENT IN MACHINES FOR MILLING HARVESTER GUARD-FINGERS.

The Schedule referred to in these Letters Patent and making part of the same.

TO ALL WHOM IT MAY CONCERN:

Be it known that I, JEROME FASSLER, of Springfield, in the county of Clark, and State of Ohio, have invented a new and useful Improvement in Machines for Milling Harvesters' Guard-Fingers; and I do hereby declare the following to be a full, clear, and exact description of the same, reference being had to the accompanying drawings, in which—

Figure 1 is a front elevation of my machine.

Figure 2 is an end elevation of the same.

Figure 3 is a vertical longitudinal section of one of the clamping-blocks or holders to hold the fingers while being milled.

Figure 4 is a side elevation of one of guard-fingers as forged.

Figure 5 represents the finger after being milled, in side and front view.

That others may understand my invention, I will particularly describe it.

My invention consists in the construction of a machine designed and adapted particularly to the manufacture of harvesters' guard-fingers, and its elements may be recounted as follows: first, in mounting the main shaft upon which the cutter-heads are placed upon a vertically moving carriage, so that the cutters may be adjusted to the height of the work; second, placing the bearings of the main shaft all between the gearing on one end and the cutter-heads on the other; third, the construction of the holding-block and manner of holding the guard-fingers therein; fourth, the arrangement of the carriage upon which the work is carried under the cutters; fifth, the arrangement of the automatic feeding mechanism and let-off.

The frame of my machine consists of a cast-iron bed-plate, A, and back A', supported upon four legs B. The back A' is planed on its edges and face, and the former are made parallel, and receding at an acute angle from the face in the form known as dove-tailed. A vertical recess is made up and down its centre as at C, and within this recess is placed the adjusting-screw D, by means of which the cutters may be raised or lowered to adjust them properly to their work. The hand-wheel E, at the top of the screw D, serves to rotate the said screw as desired. The carriage F is fitted to the face of the back A', and at its rear is a dove-tailed recess fitted to and corresponding with the edges of said back, so that when this carriage is in position it may be moved freely along the face of the back in a vertical direction, but will not move in any other direction without the removal of portions of the frame, &c., for the purpose. The screw D passes through a nut attached to the back of the carriage F, which is thereby raised or lowered when the said screw is rotated. The main shaft G and counter-shaft H are both mounted in boxes I I I I, on the front of the carriage F, so that as the carriage is moved up and down the distance between these two shafts remains unchanged, and their connecting gear-wheels J and K are always in mesh. L and M are fast-and-loose pulleys, upon which the main driving-belt N runs and communicates motion to the working parts of the machine. Upon the end of the main shaft opposite to the gear-wheel J the milling cutters are placed. This end of the shaft G is projected beyond the edge of the carriage F far enough to receive all of the sections of the cutter, which are retained thereon by a screw-nut. This end of the main shaft is also made considerably larger and stiffer than the remainder of the shaft, so that it may have strength to resist the lateral strains to which it will be subjected. The cutters O O are made in sections of about one inch in thickness, more or less, and the cutting edges are usually arranged as shown in fig. 1, i. e., part diagonal to, and part parallel with, the axis of the shaft G, so that the cutters will commence to cut at one edge sooner than at the other, and thus make the operation continuous instead of intermittent, as would be the case if all of the cutting edges were parallel with the axis of the shaft. The machine suffers much less strain, and less power is required to operate it, in consequence of this arrangement of the cutting edges. The cutters are made thin, because if a cutting edge fails in consequence of defective tempering or other cause, it causes comparatively small loss, as the broken section can readily be replaced with a perfect one. The use of thin sections also enables me to arrange offsets in the work in such positions as I desire, and to change their positions when required, without the trouble and expense of manufacturing cutters specially adapted to the division of the surfaces to be milled. By arranging the cutters upon the projected end of the shaft G, I am also enabled to use much smaller cutters than would be feasible if the shaft G had a support outside of said cutters, as said support would necessarily interfere with any clamping device which might be required to hold the work close to

the cutters, if small cutters should be used. Upon that portion of the frame A which is beneath and transverse to the axis of the cutters O, is placed the carriage P, which bears the work to be milled. The carriage P moves in guide-ways planed in the upper surface of the frame A, and is moved back and forth by the screw upon the outer end of which is the hand-wheel R, through which motion is communicated. The edge of the hand-wheel R is gear-cut on its periphery, so as to mesh with the endless screw S. Motion is communicated to the shaft of this screw by the belt T, from the shaft H, so that when the screw S and wheel R are in mesh, the work will be fed under the milling cutters automatically, and when they are not in mesh, the carriage P may be run forward or back by turning the wheel R with the hand. That end of the shaft of the screw S which is opposite the pulley end, is mounted in a dropping-box, U, which has a vertical movement in the block V, which movement serves to throw the screw S in or out of gear with the wheel R, as the case may be. It is held up so as to retain the screw S in mesh by the hook W, which depends from the front end of the rod X. The rod X has an endways motion in bearings beneath the frame A, conveniently made by passing it through suitable holes made in the legs B B. When the rod X and the hook W are drawn forward, the said hook may catch under the box V and hold it up, so that the screw S will be in mesh with the wheel R, and if the hook W and rod X are pushed back, as shown in red lines in fig. 2, the box U will drop of its own weight and throw said screw and wheel out of gear. This stop motion is rendered automatic by placing at the rear end of the carriage P a stop-pin, Y, which at a certain time will come in contact with an arm, Z, attached to the rod X, causing said rod to be withdrawn with its hook W, thus releasing the box U, which will fall and throw the screw S and wheel R out of gear. The stop-pin Y may be made adjustable so as to be set out or in as desired to stop the feed sooner or later. Across the front edge of the carriage P transverse to its line of movement is the ledge a, which is wider on its top than at its base, and overhangs the base on its inner or rear side, as clearly shown in fig. 2, where its end is seen. And at the rear side of the said carriage is secured by suitable means the screw-nut box b, through which passes the binding or clamping-screw d. Between this screw and the ledge a the work or the work-holder is secured.

I have now described the construction of my machine and its mode of operation, and will next describe the work which it is designed to perform.

The guard-finger e is forged or otherwise formed approximately in the form it is to bear when finished. I prefer to form them as nearly as possible in the form represented in dotted lines in fig. 4, so far as the surfaces to be milled are concerned. It is necessary to the economical manufacture of harvesting machinery, and especially the cutting apparatus for harvesters, that the guard-fingers should be dressed with perfect uniformity on all their surfaces, especially those which are to be placed in contact with the finger-bar and nail-rod, because, as must be manifest, if the fingers are not thus uniformly formed, they will either require more or less work to be bestowed upon each one separately in order to fit it, or they will stand irregularly when secured to the finger-bar. By dressing these surfaces in the manner described, they are rendered as nearly uniform as the state of the art permits, because each successive tooth is passed under the same cutters, and must therefore be of the same form and configuration. In manufacturing harvesters' guard-fingers, the milling of these straight surfaces is the first operation after the forging, and the milled surface is made the basis from which the subsequent operations of drilling and sawing are commenced and gauged. The holding-bed or frame g is a heavy block of metal with recesses formed in its upper surface, which correspond in shape to the form of the under surfaces of the guard-fingers. The form and relative position of said recesses are shown in fig. 3. An iron bridge, h, surmounts this bed-plate, and through it are passed as many screw-holes as there are to be fingers placed in this holder. Into these screw-holes are placed the binding-screws i i, which are of graduated lengths, as shown in figs. 1 and 2, so that when "set home" the heads may rise to different heights above the bridge h, and thus afford facilities for convenient use of the wrench when it is required to alter the pressure of any single screw. The holding-block g has along its side a re-entrant rabbet to correspond with the form of the ledge a, and on its other side is a conical indentation into which the end of the screw d enters to clamp the block g fast to the carriage P. The ledge a from its form tends to clamp the block g down upon the surface of the carriage, and the conical point of the screw d also does the same. It is desirable that the top surface of the guard-finger should not be marred by the mark which would be left by the point of a binding-screw, and I therefore use blocks m, with curved tails or handles, for convenient handling, to place between the guard-finger and the point of the binding-screw i. The use of the block m serves another useful purpose also: a much less movement of the binding-screw i is required to free and remove the guard-finger than would be the case if the blocks were not used, as with them it is only required to slacken the screw enough to free its point, when the block m may be readily removed, and space left for the ready removal of the guard-finger. In operating this machine economically two hands or attendants are required, one to remove the guard-fingers from one holder and replace blanks therein, while the other is mounting and operating the machine, two or more holders g being provided for each machine.

Having described my machine, its construction and operation, what I claim as new, and desire to secure by Letters Patent, is—

The combination of the main shaft G, which carries the cutters, and the counter-shaft H, which receives motion from the driving power, both mounted upon the carriage F, with the feed-shaft S, constructed and arranged substantially in the manner shown.

The arrangement, substantially as shown, of the main shaft G and counter-shaft H, both upon the vertically moving carriage F, cutters O O, gearing J K, and pulley L, all outside of the bearings of said shafts.

Securing the guard-finger e to the holding-bed g in the manner shown, to hold them firmly while being faced off by the cutters.

The combination of the detachable holding-bed g with the carriage P, whereby duplicate holders may be used, and one set being prepared while another is being operated upon, in the manner shown and described.

The detachable holding-bed *g*, carriage *P*, and feed-screw *Q*, combined with the hand-wheel *R*, worm *S*, and driving-band *T*, all combined for joint operation substantially as shown.

The combination of the set-stop *Y*, let-off device *W X Z*, and dropping-box *U*, to stop the movement of the carriage *P* at the desired point.

The detachable holding-block *g*, in which two or more guard-fingers may be secured at one time, in combination with the carriage *P* and cutters *O* of a milling machine.

JEROME FASSLER.
